Filed July 9, 1970, Ser. No. 23,879

Term of patent 14 years

Int. Cl. D3—02

U.S. Cl. D87—3

FIG. 1 is a top plan view of a card ejector case, or similar article, showing new design;

FIG. 2 is a side elevational view thereof;

FIG. 3 is a bottom plan view;

FIG. 4 is a front elevational view;

FIG. 5 is a rear elevational view; and

FIG. 6 is a perspective view thereof showing one of the card-holding frames in an ejected position.

The design is characterized by the combination of a plurality of vertically arranged and laterally offset knurled control elements with an open top and an open edge on the card case, all as shown.

I claim:

The ornamental design for a card ejector case, or similar article, as shown and described.
